Patented Mar. 31, 1964

197,842

COMBINED STEP AND STOOL

Walter T. Keller, Mission Woods, Kans., and Robert L. Wehner, Kansas City North, Mo., assignors to Cramer Posture Chair Company, Inc., Kansas City, Mo., a corporation of Missouri

Filed Nov. 13, 1962, Ser. No. 72,478

Term of patent 14 years

(Cl. D15—8)

Fig. 1.

Fig. 2.

Fig. 3.

FIG. 1 is a perspective view of a combined step and stool design embodying this invention.

FIG. 2 is a side elevation thereof.

FIG. 3 is a top view thereof.

The lines on the upper surfaces of each section of the combined step and stool as shown in FIGS. 1 and 3 are to indicate ribbed areas thereon and the relative direction of the ribs thereof.

We claim:

The ornamental design for a combined step and stool, as shown and described.
